DESIGN FOR A HOSIERY DISPLAY DEVICE

Milton M. Halpern, New York, N. Y.

Application October 21, 1947, Serial No. 142,054

Term of patent 3½ years

(Cl. D80—9)

To all whom it may concern:

Be it known that I, Milton M. Halpern, a citizen of the United States of America, and a resident of the city of New York, in the county of Kings and State of New York, have invented a new, original, and ornamental Design for a Hosiery Display Device, of which the following is a specification, reference being had to the accompanying drawing, forming a part thereof:

Fig. 1 is a front elevational view of a hosiery display device showing my design.

Fig. 2 is a top plan view thereof showing one of the V-shaped hood members removed.

I claim:

The ornamental design for a hosiery display device, substantially as shown.

MILTON M. HALPERN.
